UNITED STATES PATENT OFFICE.

JOHN STASZAK, OF PULASKI, WISCONSIN, ASSIGNOR OF ONE-HALF TO MICHAEL STASZAK, OF PULASKI, WISCONSIN.

URINAL.

1,226,716.

Specification of Letters Patent. Patented May 22, 1917.

Application filed July 24, 1916. Serial No. 110,965.

To all whom it may concern:

Be it known that I, JOHN STASZAK, a citizen of the United States, residing at Pulaski, in the county of Shawano and State of Wisconsin, have invented certain new and useful Improvements in Urinals, of which the following is a specification, reference being had therein to the accompanying drawing.

The invention relates to urinals and has for its object the provision of a device of the kind set forth which will be automatically flushed during the time in which a person is in close proximity to the same.

A further object of the invention is to provide means for flushing the device which may be easily removed so as to give access to the floor for cleaning purposes.

Another object of the invention consists in providing mechanism which may be quickly installed and applied to devices already in use.

It forms also an object of the invention to provide certain features of construction and arrangement whereby the desirability and effectiveness of a device of this character are enhanced.

With these and other objects in view, which will be apparent as the description proceeds, the preferred embodiment of the invention consists of the novel arrangement of parts described in the following specification and specifically pointed out in the appended claims. In the accompanying drawing,

Figure 1 is a side elevation of the device to which the invention has been applied.

Fig. 2 is a front elevation of the same.

Fig. 3 is an enlarged view of the platform and the valve actuating means, and

Fig. 4 is a section on line 4-4 of Fig. 2, showing one of the adjusting screws.

Fig. 5 is an enlarged sectional view of a push valve used in connection with this invention.

In the drawing, 1 designates a receptacle of known construction and made of suitable material which is secured to the wall 2. From a source of water supply a pipe 3 leads to a valve 4 arranged close to the floor, and a pipe 5 connected to the outlet end of the valve communicates with the upper end of the receptacle, so that water, the flow of which is controlled by valve 4, is projected in streams into the receptacle to flush the same. The valve 4 is of the push valve type

and includes a stem 6 projecting therefrom adapted to be forced inwardly against a valve disk 4^a and tension of spring 4^b in order to permit the passage of water through the valve. A platform 7, arranged at suitable distance from the wall 2, is equipped with pins 8 on each side adapted to enter slots of floor brackets 9 whereby the platform is tiltably mounted for a purpose hereinafter set forth. At the opposite end 60 of the platform springs 11 are arranged at each side which surround a lug 10 at the under side of the platform, and a similar lug 10' secured to the wall so as to maintain the spring constantly in operative 65 position. It is apparent that the end of the platform adjacent the device is maintained in raised position and is only forced down when weight or pressure is applied thereto. Adjacent the springs 11 adjusting screws 12 70 are provided which threadedly engage a bushing 13 provided in the platform. By adjusting the screw 12 the range of movement of the platform may be varied within narrow limits. At the upper side of the 75 platform a plate 14 is secured which is formed integral with an ear adapted to enter a clevis 15. A pin 16 projecting through the clevis secures the same to the ear of plate 14. A rod 17 is secured to the clevis 80 or formed integral therewith, and its opposite end is threaded to receive a head or cup-shaped member 18 which is provided with a knurled portion 19 to permit adjustment of the member 18 on the rod 17. The forward 85 end of the member 18 is recessed, as at 20, to receive the projecting end of the valve stem 6.

The operation of the device will be apparent from the foregoing description. The 90 person approaching the device is forced to step upon the platform which under this weight is pressed downwardly until the lug 10 abuts the lug 10'. Due to this movement a rod 17 receives a slight movement toward the wall in which the valve stem 6 participates to open the valve disk 4^a, and water may freely pass through the pipe 5 into the receptacle to flush the same. As soon as the person leaves the platform a spring 11 95 forces the forward end of the platform upwardly, whereby the cup-shaped member 18 is retracted and the valve stem 6 is forced outwardly under the influence of a spring 4^b located within the valve casing. A tri- 100 105 110

angularly shaped piece 21 is arranged in front of the platform so as to facilitate stepping on the latter and to prevent a person from being tripped by the lower edge of 5 the platform.

It is quite frequent that the floor becomes soiled and wet, and for this reason it is desirable that the mechanism provided in front of the device should be easily removable, so 10 as not to interfere with a person cleaning the floor. To this end the platform 7 may be swung about the pins 8 to a position indicated in dotted lines in Fig. 3, in which the cup-shaped member is sufficiently retracted 15 to entirely clear the valve stem 6. Thereupon the platform may be withdrawn from the floor brackets 9 and may be removed until the floor has been cleaned.

It is not my intention to confine myself to 20 the precise details shown by way of example in the drawing, but I want to avail myself rather of any departures, changes or alteration which fairly fall within the scope of the invention, as defined by the appended claims.

5 I claim:—

1. In a device of the type set forth, a receptacle, a pipe leading into said receptacle, a push valve controlling the flow of water

through said pipe, a tiltably mounted platform detachably secured, a rod pivotally secured to the platform, and a cup-shaped member secured to said rod and adapted to actuate said valve. 30

2. In a device of the type set forth, a receptacle, a pipe leading into said receptacle, 35 a push valve controlling the flow of water through said pipe, a tiltably mounted platform detachably secured, a rod pivotally secured to the platform, and a cup-shaped member adjustably secured to said rod and 40 adapted to actuate said valve.

3. In a device of the kind set forth, a receptacle, a pipe leading into said receptacle, a push valve controlling the flow of water through said pipe, a tiltably mounted platform, 45 resilient means for maintaining the platform in raised position, means for varying the range of movement of said platform, a rod pivotally secured to the platform, and a cup-shaped member adjustably secured to 50 said rod and adapted to actuate said valve, substantially as described.

In testimony whereof I hereunto affix my signature.

JOHN STASZAK.
